EYE SHIELD

Marion L. Potts, 2601 Chrysler Drive, Detroit, Mich.

Filed Mar. 24, 1965, Ser. No. 84,428

Term of patent 14 years

(Cl. D57—1)

FIG. 1

FIG. 2

FIG. 3

The broken line showing of the human head in FIGURE 1, is for illustrative purposes only.

I claim:

The ornamental design for an eye shield, substantially as shown and described.
